Inventor;

Bayntun J. Higgins.

UNITED STATES PATENT OFFICE.

BOYNTON J. HIGGINS, OF BOSTON, MASSACHUSETTS, ASSIGNOR OF ONE-HALF TO ISAAC H. RANDALL, OF SAME PLACE.

NECKTIE-FASTENER.

SPECIFICATION forming part of Letters Patent No. 352,130, dated November 9, 1886.

Application filed April 3, 1886. Serial No. 197,726. (No model.)

To all whom it may concern:

Be it known that I, BOYNTON J. HIGGINS, a citizen of the United States, residing at Boston, in the county of Suffolk and State of Massachusetts, have invented a new and useful Necktie-Fastener, of which the following is a specification, reference being had to the accompanying drawings.

My invention relates to a fastener which may be readily applied to neckties of a common and well-known form, and which is adapted to hold the necktie in place by clasping the ordinary collar-button; and it consists in the devices and combinations hereinafter set forth, and specifically pointed out in the claims.

In the drawings, Figure 1 shows the inner face of the fastener when the fastener is applied to a necktie and the spring-wire or clasp is in position to embrace the neck of a collar-button, the necktie being indicated by dotted lines. Fig. 2 shows the inner face of the fastener before the fastener is applied to the necktie, the spring-wire or clasp having been thrust upward. Fig. 3 is a plan or top view of the plate without the spring-wire or clasp. Fig. 4 is a view of the outer face of the fastener, being that face which is to be against the necktie-back. Fig. 5 shows the inner face of the plate of the fastener. Fig. 6 shows the spring-wire or clasp.

The plate A, or body of the fastener, may be of one piece, and may be struck up out of thin sheet metal. It is provided with a raised portion or guard, a, an opening, b, three prongs, c, extending outward, and two projections, d and e, extending inward. The prongs c are to enter the necktie-back and to be bent down upon the same, inclosing the back between the prongs and the plate A and holding the fastener firmly on the necktie, as illustrated in Fig. 1, the necktie-back being indicated by the dotted lines f. The raised portion a and the opening b allow the spring-wire or clasp B to lie between the upper or raised portion and the necktie-back, while it extends over the lower part of the plate, this raised portion a serving as a guard to prevent the spring-wire or clasp from being bent inward. Each of the projections d and e has a hole to receive

one limb, g, of the spring-wire or clasp. The projection e has an elongated opening to receive the limb h of the spring-wire or clasp.

The clasp B may be formed of one piece of wire, being of the nature of a spring, so that the two limbs g and h have a tendency, when pressed toward each other, to spread apart. One limb, g, is of sufficient length to slide the required distance while held in the projections d and e, and the other limb, h, of a length to be conveniently grasped below the projection e. At the upper end of the clasp the wire thereof forms a loop or opening, i, smaller than the head of the collar-button, and below this an opening, j, sufficiently large to receive said head. The limb h is bent or formed, whereby it is provided with a hook at k, as shown.

The fastener having been secured by means of the prongs c to the necktie-back, as specified above, in operation the spring-wire or clasp is slid upward, so as to allow the head of the collar-button to enter the opening j. It is then pulled downward, so that the upper part of the clasp passes behind the button-head and the hook k below the projection e. Thus the necktie is securely held, since the button-head cannot pass through the opening formed by the upper part of the clasp, and the upper edge of the guard a or the clasp slide upward, since the hook k engages with the end or outer edge of the projection e.

I claim as my invention—

1. In combination with a plate, A, provided with projections d and e, having the openings therein specified, a clasp, B, having the two limbs g and h, forming the smaller loop or opening, i, and the larger opening, j, substantially as and for the purposes set forth.

2. In combination with the plate A, provided with the projections d and e, raised portion or guard a, and prongs c, the spring-wire or clasp B, having the two limbs g and h, forming the loop or smaller opening, i, and the larger opening, j, and provided with a hook, k, substantially as specified.

BOYNTON J. HIGGINS.
